UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR ROOF.

Application filed January 28, 1924. Serial No. 689,093.

To all whom it may concern:

Be it known that I, WILLIAM D. THOMPSON, a citizen of the United States of America, residing at Detroit, in the county of Wayne and State of Michigan, have invented certain new and useful Improvements in Car Roofs, of which the following is a specification, reference being had therein to the accompanying drawings.

10 The invention relates to car roofs of the type known as "flexible" in which load sustaining metallic roofing sheets are relatively movable and are provided with weather-proofing means. It is usual to provide such 15 roof frames with gusset plates or other means for holding the same square with the car ends, such means being independent of the overlying roof. The present invention dispenses with such independent bracing 20 means and secures the necessary bracing and the squaring of the frame by a rigid portion of the weather-proofing roof. The roof as a whole is not, however, rigid, as the rigid panels are limited to the end 25 portions only of the frame, while the main portion is covered by a flexible roof. Thus by combining these flexible and rigid elements, I secure all the desired flexibility, together with the requisite rigidity and 30 squaring of the frame and with a simplified construction.

In the drawings:

Figure 1 is a plan view of a portion of the roof frame;

35 Figure 2 is a cross-section thereof;

Figures 3 and 4 are longitudinal sections on lines 3—3 and 4—4 respectively of Figure 5;

40 Figure 5 is a cross-section in a different plane from Fig. 2.

In the construction of Figures 1 to 4, A are the side plates of the car, which as shown are metallic Z bars. B is the car end shown as a metallic plate construction. C are 45 metallic carlines of inverted channel cross-section extending from side plate to side plate, D are purlins extending longitudinally and secured to said carlines and R is the ridge pole. The side plates A, carlines 50 C, purlins D, and the ridge pole R constitute the skeleton frame upon which the roof is supported.

55 At the end of the car extending across the same between the side plates is a metallic panel E. This preferably conforms to

the general slope of the roof from ridge to eaves and is provided with depending flanges E' overlying the side plates and riveted or otherwise rigidly secured thereto. There is also a depending flange E² for 60 securing to the car end, or, if desired, this flange and the panel may form an integral portion of the car end, as shown in Figure 3. The inner edge of the panel E is provided with an upstanding flange F terminating in a laterally extending flange G, which portions form in effect a carline and conform to the general shape of the carlines C.

Overlying the skeleton portion of the car frame is a flexible metallic car roof of any 70 suitable construction, but as shown, this comprises load sustaining metallic roofing sheets H extending from the ridge to the eaves, being provided with upstanding flanges H¹ and H² at the ridge and the sides 75 thereof and a depending return-bent flange H³ at the eaves. The latter has a hooked engagement with the depending facia flange I which retains the sheet from endwise displacement. Weatherproofing caps J embrace 80 the upstanding flanges H¹ H² of adjacent sheets and also embrace the intermediate carlines. Ridge caps K embrace the upstanding flanges at the ridge and junction caps L secure the carline caps and ridge caps in 85 position and weatherproof the joint therebetween. The plate H, which is adjacent to the panel E, is provided with a depending end flange H⁴, which is bolted or otherwise secured to an end facia plate M, this being 90 secured to the flange F.

With the construction as described, in service, all of the roof, with the exception of the portion formed by the panels E, is free to flex, the plates H being relatively movable 95 to each other and to the roof frame. This will prevent overstressing any portion of the roof through the weaving or distortions of the roof frame. On the other hand, the panels E are of sufficient strength to hold the roof 100 frame square at the ends and are of sufficient strength to withstand any stresses to which they are subjected.

What I claim as my invention is:

1. In a car roof, the combination with a 105 skeleton frame, of a roof overlying said frame comprising in the main relatively movable metallic roofing sheets and weather-proofing means therefor, and a metallic panel forming a portion of the roof rigidly at- 110

- tached to said frame and serving to brace the same.
2. In a car roof, the combination with a skeleton roof frame, of a flexible car roof 5 overlying the major portion of said frame, and a metallic panel forming a complementary portion of said roof rigidly secured to said frame and serving to brace the same.
3. In a car roof, the combination with a skeleton roof frame, of a metallic panel arranged at the end of said frame rigidly attached to the side plates, roof frame and ends of the car and forming a weatherproof portion of the roof, and a flexible roof overlying the remainder of the frame and secured thereto.
4. In a car roof, the combination with a skeleton roof frame comprising side plates, car ends, carlines and purlins, of a metallic 20 panel extending across the end portion of the roof, being rigidly secured to the side plates, purlins and car end and serving to brace the latter, and a flexible roof comprising relatively movable load sustaining roofing sheets and weatherproofing means overlying 25 said skeleton frame and complementary to the portion of the roof formed by said panel.
5. In a car roof, the combination with a skeleton roof frame including side plates and a metallic car end, of a metallic panel 30 forming an extension of said car end overlying the end portion of said frame and rigidly secured to the side plates thereof, and a flexible car roof composed of relatively movable load sustaining roofing sheets and weatherproofing means therefor, said flexible 35 roof overlying the skeleton portion of said frame and being complementary to said rigid panel.
6. In a car roof, the combination with a skeleton roof frame comprising side plates, car ends, carlines and purlins, of a metallic panel extending between the side plates adjacent to the end of the car and rigidly connected to said side plates and end, the inner 40 edge of said panel being fashioned to form a complementary carline, and a flexible roof comprising relatively movable load sustaining roofing sheets, and weatherproofing means therefor, said flexible roof overlying 45 said skeleton frame and being complementary to said rigid panel.

In testimony whereof I affix my signature.

WILLIAM D. THOMPSON.
